[57] ABSTRACT

A sheet separating device for a stack of sheets having feed and retard means forming a nip includes an insert held against the free end of the stack. The insert is moved into contact with the retard means to release its force on the last sheet, facilitating feeding of the last sheet.

SHEET SEPARATING DEVICE

RELATED APPLICATIONS

This application is related to co-assigned:

U.S. patent application Ser. No. 137,775, entitled BOTTOM SCUFF SHEET SEPARATING DEVICE, filed Dec. 24, 1987, in the names of John Giannetti, Jerry F. Sieve and Robert H. Shea;

U.S. patent application Ser. No. 137,776, entitled DUPLEX DOCUMENT HANDLER, filed Dec. 24, 1987, in the names of John Giannetti, Robert L. Couture, Jerry F. Sieve and Robert H. Shea; and

U.S. patent application Ser. No. 137,777, entitled DOCUMENT SHEET SUPPORT MECHANISM, filed Dec. 24, 1987, in the names of John Giannetti, Jerry F. Sieve and Timothy H. Kelley.

TECHNICAL FIELD

This invention relates to a device for separating a sheet from a stack, and more specifically to a device that prevents double feeds when more than one sheet is present in the stack, but permits feeding of a single or the last sheet of a stack without damage to the sheet.

BACKGROUND ART

Scuff sheet separators typically include a feed means, for example, a belt or a roller, having a high coefficient of friction, which frictionally engages and separates the outside sheet from a stack. To prevent double feeds a retard means is placed opposite and forms a nip with the feed means. Typically the retard means has a coefficient of friction intermediate that of the feed means and the sheets. It may be stationary or be rotatably driven opposite to the feed means. The retard means retains any second sheet drawn into the nip because the outside sheet preferentially slides on the retarded second sheet. When only one sheet is in the nip the higher coefficient of friction of the feed means dominates that of the retard means and the sheet is fed. To accommodate sheets of different thickness the retard means is commonly mounted to be pivoted or otherwise moved away from the feed means by the sheets. See, for example, U.S. Pat. Nos. 2,273,287; 3,831,928; 3,984,095 and 4,544,147. Unfortunately, the competing frictions on the single or last sheet have a tendency to damage it if the retarding friction is high enough to reliably separate sheets.

U.S. Pat. Nos. 2,665,906 and 4,480,827 disclose top scuff separating devices in which the problems of slippage when feeding the final sheet have been reduced by use of a braked retard roller opposite a larger drive roller. The brake force on the retard roller is such that the retard roller rolls only when subjected to the increased tangential force of a single sheet or no sheet being in the nip.

DISCLOSURE OF THE INVENTION

It is the object of the invention to provide a sheet separating device similar to the types described which applies substantial retarding force to prevent double feeds, but which has greater reliability in feeding the last sheet.

This and other objects are accomplished by a device having feed means for engaging and frictionally feeding the outside sheet from a stack, retard means movably mounted to provide a nip with said feed means through which said outermost sheet is conveyed, and an insert positioned to engage the end of the stack opposite the

feed means. The insert is so positioned and mounted that it is frictionally moved by the last sheet to be fed into engagement with the retard means to provide a lifting force to the retard means to reduce the frictional retard force of the retard means on the last sheet.

According to a preferred embodiment, the insert is a flat sheet-like member attached to a portion of a housing associated with a receiving means for the stack. Preferably, the housing to which the insert is attached is a movable cover, which, when closed, positions the insert in engagement with the stack.

According to a further preferred embodiment, the separation device is of the bottom feeding type toward which co-filed application Ser. No. 137,775, entitled BOTTOM SCUFF SHEET SEPARATING DEVICE to John Giannetti, Jerry F. Sieve and Robert H. Shea is directed. The feed means is a belt and the retard means includes at least one braked roller. The braking force on the roller is chosen to prevent turning of the roller when more than one sheet is in the nip, but permits turning when one or no sheets are in the nip. Although this structure has great latitude in feeding sheets of varying weight and condition, that latitude is extended by provision of an insert according to the invention which will reduce the downward force of the retard means when feeding the last sheet.

BRIEF DESCRIPTION OF THE DRAWINGS

FIGS. 1 and 2 are schematic side views of a sheet separating device constructed according to the invention.

FIG. 3 is a perspective view of a copier which includes a document handling mechanism in which the invention is particularly usable.

FIG. 4 is a side view of a feeder and scanner constructed according to co-filed application, Ser. No. 137,775 to Giannetti et al, mentioned above, with support structure and other parts eliminated for clarity.

FIG. 5 is a top view of a portion of the apparatus shown in FIG. 4 with parts eliminated for clarity.

FIG. 6 is a side view of a portion of the apparatus shown in FIG. 4 with parts eliminated for clarity.

FIGS. 7 and 8 are perspective views of the apparatus shown in FIG. 3 with certain elements in different operating positions.

FIGS. 9 and 10 are top and right vertical views respectively showing detail of a registration roller shown in FIG. 4.

FIG. 11 is a side view similar to FIGS. 4 and 6 constructed according to this invention.

FIGS. 12 and 13 are side and top views, respectively, of an insert shown in FIG. 11.

BEST MODE OF CARRYING OUT THE INVENTION

The basic concept of the invention is best illustrated by schematic FIGS. 1 and 2 in which a sheet separation device 201 includes feed means, for example, a feed belt 202. The belt 202 is positioned to engage and frictionally feed the outside sheet from a stack 203. Retard means, for example, a pivotably mounted non-rotatable roller 204, rests by gravity or is spring urged against belt 202 to form a nip through which the outermost sheet is conveyed. Roller 204 may also be tendency driven to tend to rotate in the opposite peripheral direction as the belt 202 as is known in the art.

As shown in FIG. 1, the stack 203 includes four sheets, and the belt 202 is separating the bottom sheet by feeding it frictionally to the right. The second sheet has been pulled by the bottom sheet to a point at which it is entering the nip. At this point the retard means which has a greater coefficient of friction than the sheets themselves prevents further movement of the second sheet and the bottom sheet slides on the second sheet and is separated from the stack.

As shown in FIG. 2, when all sheets except one have been separated, prior devices relied upon the greater coefficient of friction of the feed means, belt 202 to dominate the coefficient of friction of the retard means 204. The last sheet then slides on the retard means and is fed by the belt.

However, the difficulty in feeding the last sheet is a significant limiting aspect of these devices, because of the tendency of the competing frictions to damage the sheet. This is especially true when feeding a used or light weight sheet as is often required in a document handler. According to the invention, an insert 205 supported by a portion of the housing 207 through weak springs 206 rests on the end of the stack opposite the feed means, in this case, the top of the stack 203, and is held there by gravity. As shown in FIG. 2, when the last sheet is to be fed, the belt 202 moves the sheet into the nip with the retard means 204. This movement carries the insert 205 toward the nip and into contact with the retard means 204 camming it in an upward direction. Although there still may be contact between the retard means and the last sheet, its frictional retard force is greatly reduced, thereby permitting feeding of sheets of much lighter weight and more fragile condition.

Because this invention has particular application to a sheet separation device toward which above referenced co-filed application to Giannetti et al is directed, the preferred embodiment of this invention will be better understood if that invention is explained thoroughly. Accordingly, FIGS. 4-6 show that device as disclosed in said application and without the invention, i.e., without the insert 205. FIGS. 11-13 show the invention in this application, i.e., the insert applied to the FIGS. 4-6 apparatus. The other Figs. show a scanner for a copier with a sheet handling device in which the invention is particularly well adapted for use.

According to FIG. 3, a copier 1 is made up of a printer 2 and a scanner 3. The scanner 3 includes a document handler 4 and an optical system enclosed in an optics housing 5.

Referring to FIG. 4, the optical system includes an illumination head 7 containing an exposure radiation source 8, an elliptical reflector 9 and a plane reflector 10. The illumination head 7 cooperates with a pair of movable mirrors 11, an objective 12 and an electrooptical image sensor having separately addressable pixels, for example, a CCD 13. Objective 12 and CCD 13 are stationary while the illumination head and pair of movable mirrors are movable from the position shown in solid lines to the position shown in phantom in FIG. 4.

When the illumination head 7 is located in the position shown in solid lines in FIG. 4, it is positioned to project onto CCD 13 an image of a moving document presented by the document handler 4 to an exposure position 15. The illumination head 7 and mirrors 11 are movable by a pulley system, not shown, to scan an image of a document or other object placed on an exposure platen 16 onto CCD 13.

The document handler 4 includes a document supply or input tray 20 into which a multisheet (or single sheet) document is placed face down. Document sheets are fed one at a time from the bottom of the stack by a scuff separating device 21 to be described more fully below. The input tray 20 is inclined approximately 7 degrees from the horizontal to gain the assistance of gravity in the separating process. Documents separated from the stack are fed by a pair of feed rollers 22 along an input path 23, defined by registration guides and having a registration roller 28, also described more fully below to a turnover drum 24. Turnover drum 24 is driven by drum drive rollers 25 and 27 which in turn are driven through a suitable clutch by a drive belt 55 driven by a motor 26. Drive belt 55 also drives a pulley 56, through a suitable clutch, which in turn drives the pulley system, mentioned above, for moving the optical components during platen mode copying. The document is fed across the exposure position 15 by the combined action of the drum drive rollers 25 and 27 driving both the document and the turnover drum 24. The turnover drum 24 is held tight against the drum drive rollers 25 and 27 to assure location of the document in the object plane of objective 12, also described more fully below.

If only one side of the document is to be scanned, a separator or diverter 30 is moved to a raised position which strips the document from turnover drum 24 and allows it to be fed by a simplex exit roller 31 into a simplex exit tray 32. Because the documents are placed face down in the document input tray 20 and are fed in that position across the exposure position 15 and into the simplex exit tray, and new documents are fed into the simplex exit tray on top of preceding documents, the stack of documents in the simplex exit tray ends up in the same order and orientation as in the document input tray 20.

If both sides of the document are to be scanned, diverter 30 is placed in its down position allowing the document to follow turnover drum 24. The document is held to turnover drum 24 positively by a set of belts 33 which are driven by turnover drum 24. The belts 33 also drive simplex exit roller 31 thereby maintaining constant velocity of the document in the simplex mode. In the duplex mode, the document is separated from the turnover drum 24 by a passive diverter 35 which directs the document into a turnaround path and between reversing rollers 36. The reversing rollers 36 are driven by separate means, for example, a reversible motor, not shown, and drive the document to the left as shown in FIG. 4 until the trailing edge of the document passes a sensor 37. The sensor 37 sends a signal to the drive means for reversing rollers 36, reversing the rotation of the rollers and feeding the document back to the right along the turnaround path. Passive diverter 35 now directs the document downward, between rollers 25 and 27 and across the exposure position 15 for exposure of the reverse side. As the reverse side is exposed, diverter 30 stays in the downward position allowing the document to once again continue with turnover drum 24 until directed by passive diverter 35 to feed back along the turnaround path to the reversing rollers 36. This time, reversing rollers 36, assisted by an additional duplex exit roller 42, driven by reversing rollers 36, continue to drive the document along this path until it is completely deposited into a duplex exit tray 38. A stack of duplex documents fed through this path will be stacked in the duplex exit tray 38 in the same order and

orientation in which they were placed in the document input tray 20.

The duplex exit tray has a hinge 39 which allows it to be lifted to a position shown in FIG. 7, permitting access to the document input tray 20. The document input tray 20 is part of a structure which, in turn, is fastened by hinges 40 (FIG. 7) which permits raising of a portion 34 of the document handler left of reversing rollers 36 (FIG. 4) to provide access to the exposure platen 16 as shown in FIG. 8.

Referring to FIG. 7, the document input tray 20 includes an edge guide 41 which is adjustable to assure proper location of the multipage document against a fixed edge guide 34. The adjustable edge guide 41 may also be connectable by means not shown to the logic and control of the apparatus to input the size of the original document being scanned for purposes of automatic choice of magnification, copy sheet size and the like. Alternatively, a set of document sheet size sensors may be incorporated into the input tray for determining paper length and/or width, or one or both of these dimensions may be determined from the signal from CCD 13. These approaches may be combined, for example, by using sensors or edge guide 41 to determine cross-track size and the CCD signal to determine in-track size.

The provision of separate simplex and duplex exit trays 32 and 38 provides an extremely simple, compact and low cost document handling apparatus which returns both simplex and duplex stacks to their respective output trays in their original page sequential order. Factors that contribute to these advantages include the convenient location of the duplex exit tray directly above the document input tray and utilization of the turnaround path for both turnaround of the document sheets in the duplex mode and also exit of duplex documents to the duplex exit tray 38.

The portion of the document being scanned, i.e., that portion of the document in exposure position 15 must be accurately located in the object plane of objective 12. Such location is controlled by the location of rollers 25 and 27. Turnover drum 24 is not radially constrained. More specifically, it has no shaft that is held by bearings. The drum is allowed to "float." It is urged against rollers 25 and 27 by belts 33. With this structure the drum need not be machined or mounted with the accuracy that would be required if it were axially mounted and/or driven. Accurate positioning of the document is dependent upon accurate positioning of rollers 25 and 27 which are smaller and much less costly components to precisely position and manufacture. The drum being allowed to float, it does not convey inaccuracies or lack of symmetry in its support structure to the document. It is thus not inclined to skew the document. Drum 24, as seen in FIG. 5, in fact has not center shaft.

Movement of turnover drum 24 parallel to its axis is prevented by a set of blades 57 formed on passive diverter 35 which extend into recesses 58 in the drum. Thus a single element, passive diverter 35, which can be a low cost molded element performs the functions of diverting in both directions and of restraining axial movement of drum 24.

Accurate cross-track registration of a document sheet 104 after separation against an edge guide 103 is assured by registration roller 28 shown in detail in FIGS. 9 and 10. Registration roller 28 is a soft, preferably foam rubber roller which is tapered or conically shaped. It is mounted on a shaft 102 and driven by a pulley system

101 connected to drum drive rollers 25 and 27. Shaft 102 is mounted orthogonal to the in-track direction so that the pointed edge of roller 28 drives the sheet 104 directly in the in-track direction. However, the roller 5 has an undercut 105 which permits compression of the roller by the sheet as shown in FIG. 10. This compression has a component in the cross-track direction moving the sheet toward the edge guide 103. Thus, an inexpensive soft tapered roller mounted and driven on a 10 shaft parallel to the other shafts in the system assures important cross-track registration of the document sheets.

The Giannetti application, referenced above is directed to the scuff separating device 21 shown in FIGS. 4-6. It forms the basis for the preferred embodiment of the invention shown in FIGS. 11-13 and described below. FIGS. 11-13 will be better understood after an understanding of FIGS. 4-6.

The scuff separating device 21 contributes substantially to the reliability of the document handler 4 of the scanner 3 while still being simple in construction and low in cost. Because it is a document separation device rather than an ordinary copy sheet separation device, it must work with whatever type of document sheet the user places in it. It may have to separate and feed document sheets that vary substantially in age, weight and condition.

According to FIGS. 4, 5 and 6, the separating device 21 includes a scuff feed belt 43 positioned with its top surface slightly raised from the surface of document supply tray 20. Retard separating rollers 44, 45 and 46 are positioned opposite scuff feed belt 43 and are driven only by contact with belt 43 either directly or through document sheets to be fed. The retard rollers are engaged by brake rollers 47, 48 and 49, respectively, and are held by roller arms 50, 51 and 52, respectively, which pivot about a rod 54. In the preferred embodiment of the device, the retard rollers are held against the belt 43 by their own weight and that of the braking rollers and the roller arms. Additional force from springs could be used, but in most applications unnecessarily complicates the device. The brake rollers are made of a softer material than the retard rollers. Roller arm 52, retard roller 46 and brake roller 49 have been eliminated from FIG. 6 for clarity of illustration. Brake rollers 47, 48 and 49 are urged against retard rollers 44, 45 and 46 by conventional adjustable spring and screw mechanisms which establish a fixed center distance between the brake and retard rollers and which produces a compression of the softer brake roller resulting in the desired braking force on the retard roller.

In operation, a stack of document sheets is placed face down in supply tray 20 and feed belt 43 is driven in a clockwise direction. The coefficient of friction of the feed belt 43 is sufficiently high that it has a tendency to feed at least the bottom sheet of the stack toward drive rollers 22. The coefficient of friction of the retard rollers 44, 45 and 46 is also high, i.e., it is higher than the coefficient of friction between any two sheets intended to be fed. The braking force applied by brake rollers 47, 48 and 49 is chosen such that retard rollers 44, 45 and 46 will be rotated by the belt when a single sheet of paper is between the retard rollers and the feed belt, permitting feeding of that single sheet of paper into feed rollers 22. If a second sheet of paper comes between any of the retard rollers 44, 45 or 46 and the bottom sheet of paper in the stack, the braking force on the retard roller in question is high enough to prevent rotation of the roller

until the lower frictional force between the sheets is overcome. In this instance, the retard roller will not rotate and the second sheet will remain stationary underneath the retard roller while the bottom sheet is separated and fed by belt 43. If no sheets are between the belt and the retard rollers then, the high coefficients of friction of the belt and retard rollers will cause the feed belt 43 to overcome the braking force applied by brake rollers 47, 48, and 49 and directly rotate the retard rollers. Thus, as each sheet is fed, a very small incremental rotation of the retard rollers will occur presenting a clean surface to assist in retarding. This incremental rotation is proportional to the lead edge distance between sheets as they are fanned around the retard roller at the start of a job.

This system shown in FIGS. 4-6 has a number of advantages. Unlike prior retard systems, at no time is there intended to be any slippage between the scuff belt 43, the retard rollers 44, 45 and 46 and the document sheets. Only slippage between document sheets is permitted. Thus, this system will successfully feed documents that prior systems would tear or smear. In addition, because of the high coefficients of friction on the drive and retard elements, contact pressure between the belt, rollers and sheets can be greatly reduced over conventional scuff systems, also reducing document damage. The amount of frictional retard force exerted by retard rollers 44, 45 and 46 can be adjusted by adjusting the braking force applied by the brake rollers 47, 48 and 49. The system has an extremely wide latitude of frictional forces that can be applied and still feed and separate an extremely wide latitude of types of documents. The frictional force applied by the retard rollers and also by the belt only has to be greater than the frictional force between the sheets while the braking force need only be small enough to permit turning of the roller when a single sheet or no sheet is present and large enough to prevent turning when two sheets are present. Because friction between sheets is generally quite light, this tolerance is extremely wide and allows a great latitude in materials used, rarely gets out of adjustment and permits feeding of a wide variety of types of documents. For example, the coefficient of friction for most papers is in the 0.8 to 1.0 range. In theory, the coefficient of friction on the retard rollers can be anything in excess of that. In fact, the weight of the stack adds to the frictional force between the document sheets, so that, coefficients of friction in excess of 2.0 are preferred for both the retard rollers and the scuff belt 43. No special relationship is required between the coefficients of friction of the belt and the retard rollers, as would be required in conventional scuff systems relying on slippage between a retard means and one side of a single sheet being fed.

Reliability of the system is improved by positioning retard roller 45 at a different in-track position from retard rollers 44 and 46. The distance between pivot rod 54 and the center of retard roller 45 is different from the distance to rollers 44 and 46. In addition to changing the in-track position of roller 45, this construction provides slightly different working angles between the roller arms and the direction of travel of a sheet being fed by scuff separating device 21. If two sheets are in fact fed between the belt 43 and rollers 44 and 46 those two sheets will be picked up separately by retard roller 45 and the top sheet retained while the bottom sheet continues on its path. This can happen if three sheets of paper somehow get between retard rollers 44 and 46

and the belt 43, with only the top sheet being retained by the retard rollers at that position. For example, if a stack is placed in the input tray 20 with the leading edge of one sheet well behind its adjacent sheets, both bottom sheets may be fed together, with the middle sheet eventually stopped by the downstream retard roller 45. Because of the slightly greater angle of attack between the roller arm 51 compared to roller arms 50 and 52 retard roller 45 will exert slightly more force to retard the second sheet, assuming the force applied by the braking rollers in the same. This factor also has a tendency to reduce the number of double feeds.

The angle between the roller arms 50, 51 and 52 and the sheets that are fed by feed belt 43 is quite small, for example, in the range of 15 to 40 degrees. This permits the separation and feeding of different thicknesses of paper. The location of the pivot rod 54 downstream the retard rollers, has a tendency to increase the force retarding the top sheet when the roller is not rolling, i.e., when there are two sheets in the nip, but desirably relaxes the force somewhat when the roller is rotating, i.e., when there is only one or no sheets in the nip.

It is recognized in the art that belt feed mechanisms contact a greater area of a sheet than do roller feed devices and are therefore preferred for many applications. A larger proportion of the stack weight is supported by the belt compared to the input tray which increases the force moving the bottom sheet and decreases the drag from the tray. A roller would need a much higher coefficient of friction to have the same effect. Since paper is never completely flat, the greater area reduces the probability that contact will be lost. Belts also have some tendency to be more efficient because all motion of the top of the belt is in the direction of feeding while a roller drives fully in that direction only where tangential velocity is in the feed direction.

Despite these advantages and perhaps because of lower cost, rollers are more commonly used than belts for scuff separating devices. U.S. Pat. Nos. 2,665,906 and 4,480,827, cited above, suggest top separating devices with braked retard rollers and feed rollers. However, the scuff belt described in FIGS. 4-6 has features not taken advantage of in the prior art roller or belt devices. As the belt 43 advances it tries to both rotate the retard rollers and to pivot the arms 50, 51 and 52 about rod 54. The arms deflect the belt downwards until the desired brake force is overcome allowing the rollers to turn or until friction between the sheets is overcome allowing the bottom sheet to slide on the sheet next to it. This deflection of the belt generates a high localized normal force between the sheet to be separated and the belt, which forces are not applied to the rest of the stack.

Another aspect of the use of the scuff belt unique to this structure is that it permits the use of the multiple retard system embodied in roller 45, and explained above, which greatly enhances the prevention of double feeding when trying to separate sheets from dishevelled stacks.

The ability of each retard roller to both pivot about rod 54 and to rotate is a significant aspect of the preferred embodiment of this separating device. It permits the separation device to separate sheets of varying thicknesses, an important feature of a document feeder and a limiting characteristic of prior scuff feeders. In operation, as a sheet is fed it will slightly rotate the retard roller until the roller rolls and pivots up on the

leading edge of the next (second) sheet, at which point the first sheet is advanced by the belt with the second sheet restrained by the roller. The roller stops its roll and upward pivot immediately after it lifts off the bottom sheet regardless of the thickness of the sheet. If the belt is depressed by the force of the retard roller the retard roller moves with the belt to maintain the best distance for the respective thicknesses of the sheets preventing a greater opening that might result in a double feed.

The document handling portion 4 contains a number of sensing devices 65, 66, 67, 68, 69 and 70 in addition to previously mentioned sensing device 37. These devices are generally placed at strategic points to detect either the front edge, the rear edge of a document or the lack of either at the right time, to actuate the various components downstream from those sensing devices or signal that a jam has occurred.

The entire scanner 3 is driven by three motors. Motor 26, described above, drives drive belt 55 which drives drive roller 25 through a suitable clutch and hence duplex drum 24 and associated rollers and belts. Roller 27 is connected to roller 25 to also be positively driven by motor 26. As mentioned above, motor 26 and its drive belt 55 also drive pulley 56 through a suitable clutch and pulley system, not shown, for moving illumination head 7 and the pair of movable mirrors 11, as is well known in the art. Turnaround rollers 36 and rollers abutting them are driven by a separate reversible drive motor, not shown, and scuff feed belt 43 is driven by its own drive motor, also not shown.

Drive rollers 22 are driven by the same motor driving the scuff feed belt 43. However, through a suitable clutch, not shown, scuff feed belt 43 is stopped after a document has reached rollers 22. It is started again when sensor 65 senses the trailing edge of the document. Sensor 65 is positioned to provide a suitable inter-frame, for example, 2.5 cm between the documents.

According to a preferred embodiment of the invention shown in FIGS. 11-13, the range of the separation device shown in FIGS. 4-6 is even further extended, by application of the improvement described generically with reference to FIGS. 1 and 2. According to FIG. 11, movable insert 111 is held by linking arms 112 to the underside of duplex output tray 38 functioning at this point as a cover for the input tray. Insert 111 rests on the top sheet 104 of the stack of sheets. When only the last sheet is to be fed, movement of that sheet by scuff belt 43 causes insert 111 to move lightly into contact with retard rollers 46 and 48 exerting a lifting force on them and reducing the force required to move the last sheet through the system. In this embodiment, retard rollers 46 and 48 may lift to the point that they stop rotating after a short rotation, thereby permitting the last sheet to slide past them for the rest of its feeding movement. The retard roller 47 continues to turn since it is unaffected by the insert, but more force from the sheet is available to turn it with rollers 46 and 48 urged upward.

FIG. 12 and 13 show the insert in more detail. It is a flat sheet-like member and is small enough, for example, 50×100×2 mm., to overlie the belt without substantially overlying the tray. This means that its weight increases the frictional driving force of the belt without increasing the drag that the tray exerts on the bottom sheet. It is readily made from a low friction moldable plastic. The front of the insert, i.e., the edge contacting

the retard rollers, is inclined away from the rollers to assist the camming action.

The insert has side walls 122 with slots 123 receiving pins 124 in linking arms 112. The side walls can be made higher at the rear of the insert to concentrate the weight in the rear. When the output tray 38 is lifted, the butt ends 121 of linking arms 112 engage the underside of tray 38 lifting insert 111. Initial motion of the linking arms 112 slides pins 124 towards the rear of the slots 123, but the rear weight orientation of the insert causes it to tip somewhat down at the rear as it rises and the pin to slide forward in the slots. This movement is reversed as the tray 38 is closed with the rear contacting the top sheet first to keep any forward force on the top sheet at a minimum.

Thus, the insert shown generically in Figs. 1 and 2, is added to the already robust separation device shown in FIGS. 4-6 (and toward which said Giannetti et al application is directed) to provide an additional parameter 20 that can be used to extend the capabilities of that device. These capabilities are extended by extending the range of paper that can be accommodated under various environmental conditions without damage, double feeds or misfeeds.

The invention has been described in detail with particular reference to a preferred embodiment thereof, but it will be understood that variations and modifications can be effected within the spirit and scope of the invention as described hereinabove and as defined in the 30 appended claims.

We claim:

1. A sheet separation device including:
feed means for engaging and frictionally feeding the outside sheet from a stack;
retard means movably mounted to provide a nip with said feed means through which said outermost sheet is conveyed; and
a flat sheet-like insert movably attached to a portion of a housing associated with a receiving means for the stack and positioned to engage the end of the stack opposite the feed means, the insert being so positioned and mounted that it is frictionally moved by the last sheet to be fed into engagement with the retard means to provide a lifting force to the retard means to reduce the frictional retard force of the retard means on the last sheet.

2. The device according to claim 1 wherein the housing to which the insert is attached is a movable cover, which, when closed, positions the insert in engagement with the stack.

3. A sheet separation device for separating sheets from the bottom of a stack, comprising:
a feed belt for frictionally engaging and separating the bottom sheet of a stack;
retard means movably mounted to provide a nip with said feed belt through which said bottom sheet is fed by said belt, said retard means including at least one braked roller, the braking force on the roller being sufficient to prevent turning of the roller when more than one sheet is in the nip but permit turning when one or no sheets are in the nip; and
an insert positioned to engage the top of the stack, the insert being so positioned and mounted that it is frictionally moved by the last sheet to be fed into engagement with the retard means to provide a lifting force to the retard means to reduce the frictional retard force of the retard means on the last sheet.

4. The device according to claim 3 wherein the insert is attached to a movable cover, which, when closed, positions the insert in engagement with the stack.

5. The device according to claim 3 wherein said device is part of a document handler which includes an exit tray for document sheets fed from said device, which exit tray is positioned above said separation device and is movable away from said device to permit loading of a stack in said device, and wherein said insert is attached to the underside of said tray.

10 6. The device according to claim 3 wherein said feed belt is substantially coplanar or slightly raised from an input tray upon which said stack is received, and said insert is sized and positioned to overlie said belt without substantially overlying said tray, so that the weight of said insert contributes to the frictional force between the belt and the bottom sheet in the stack, but does not contribute to the frictional force between the tray and said bottom sheet.

15 7. The device according to claim 3 wherein said insert has a front edge engageable with said retard means which is inclined away from said retard means to provide a camming surface assisting in providing said lifting force on said retard means.

20 8. A sheet separation device for separating sheets from the bottom of a stack, comprising:

feed means for frictionally engaging and separating the bottom sheet of a stack;

retard means movably mounted to provide a nip with said feed means through which said bottom sheet is fed by said belt, said retard means including at least one braked roller, the braking force on the roller being sufficient to prevent turning of the roller when more than one sheet is in the nip but permit turning when no sheets are in the nip; and

10 an insert positioned to engage the top of the stack, the insert being so positioned and mounted that it is frictionally moved by the last sheet to be fed into engagement with the retard means to provide a lifting force to the retard means to reduce the frictional retard force of the retard means on the last sheet allowing the last sheet to be fed while sliding on the retard means.

9. The device according to claim 8 wherein said feed means is a feed belt substantially coplanar or slightly

25 raised from an input tray upon which said stack is received, and said insert is sized and positioned to overlie said belt without substantially overlying said tray, so that the weight of said insert contributes to the frictional force between the belt and the bottom sheet in the stack, but does not contribute to the frictional force between the tray and the bottom sheet.
